(57) **CLAIM**

The ornamental design for a faucet body, as shown and described.

DESCRIPTION

FIG. 1 is a perspective view of a faucet body showing my design;

FIG. 2 is a front faucet body view thereof;

FIG. 3 is a rear faucet body view thereof;

FIG. 4 is a left side faucet body view thereof;

FIG. 5 is a right side faucet body view thereof; and,

FIG. 6 is a top plan view thereof.

The broken line showing of the interior of the spout is for illustrative purposes only and forms no part of the claimed design.
